UNITED STATES PATENT OFFICE.

ARTHUR J. EVERE, OF CHICAGO, ILLINOIS, ASSIGNOR TO EVERE-SAUVAUGE COMPANY, OF CHICAGO, ILLINOIS, A CORPORATION OF ILLINOIS.

SHEET CUTTING AND TRANSPORTING APPLIANCE.

Application filed February 28, 1924. Serial No. 695,844.

The present invention relates to improved and novel means for transporting or cutting and transporting sheets of material by suction means particularly sheets of more or 5 less porous material, such as cloth.

The invention is especially, but not restrictedly, adapted for satisfactory and economical employment in the cutting of cloth in pattern sections and conveying the 10 severed parts and stacking them in corresponding piles.

One aim of the invention is the provision of a machine of this character which is relatively simple in structure, which is comparatively economical to produce, which is 15 unlikely to become damaged or injured in service, and which performs its functions effectively and efficiently.

To the accomplishment of these and other 20 desirable objects, the preferred embodiment of the invention presented in the accompanying drawings has been developed, this appliance being depicted in the several views of the drawings in which like reference 25 characters have been used to denote the same parts of the mechanism.

In these drawings:

Figure 1 is a side elevation of the improved cloth cutting and conveying machine;

Figure 2 is a plan view of the same;

Figure 3 is an enlarged, fragmentary, side elevation of the machine;

Figure 4 is a vertical cross-section on line 35 4-4 of Figure 1 on an enlarged scale;

Figure 5 is a vertical cross-section on an enlarged scale on line 5-5 of Figure 1;

Figure 6 is an enlarged fragmentary elevation showing the valve-mechanism and 40 associated and adjacent parts;

Figure 7 is a bottom plan view of the upper or movable cutter;

Figures 8 and 9 show parts of the suction conveyor, Figure 8 being a partial vertical cross-section and Figure 9 being a fragmentary bottom plan view on an enlarged scale;

Figure 10 shows the cam mechanism for raising and lowering the tracks or rails on 50 which the suction carriage reciprocates; and

Figure 11 illustrates the cloth gripping and feeding structure.

Referring to these drawings, it will be perceived that the appliance includes a suit-

ably-shaped main-frame 21 having at each 55 side an upstanding, guiding part 22, 22 which define the vertical movements or reciprocations of an upper, hollow, reenforced blade or cutter support 23 fitted with guide-blocks 24, 24 on opposite sides of and co-operating with the stationary, vertical guides 22, 22.

At one end, the main-frame is supplied with an appropriately-journalled, pulley and belt driven, drive-shaft 25 equipped at one 65 end with a pinion 26 in mesh with a large gear 27 mounted to revolve on a stationary cross-shaft 28 supported in bearings in the main-frame, this gear meshing with a like gear 29 on a second, corresponding, fixed 70 cross-shaft 31.

Internally each gear 27 and 29 has a cam 32 on its hub and these two interfitted elements are mounted on the hub 33 of an eccentric 34 revolvably mounted on the end or 75 protruding part of the shaft and held against displacement by a retainer-plate or cap 35, the three members, gear, cam and eccentric being rigidly secured together by a pin 36. 80

Each such eccentric has an eccentric-link 37 equipped with an aperture or bearing receiving the eccentric and having rocking connection with a shaft 38, extended through the cutter-support 23, through an interposed 85 bushing or sleeve 39.

At the opposite side of the machine, the two shafts 28 and 31 have similar intermeshing large gears 41 and 42 supplied with corresponding eccentrics 43, cooperating 90 with like eccentric links 44 rockingly mounted on the opposite ends of the two shafts 38, the gear 41 meshing with a drive-pinion 45 on the other end of shaft 25.

Thus it will be seen that the rotation of 95 the gears and the four eccentrics effects the vertical reciprocation of the member 23.

On its under side or face this perpendicularly-slidable element 23 carries a plurality of cutter or knife blades 46 arranged 100 in any desired form or pattern between spacing and holding blocks 47 in much the same manner in which rule lines are held in operative position in the form of a printing-press.

These blades, by coaction with a flat metal plate 48 on the top of the reenforced or ribbed bed or table portion of the main-

frame, are adapted to cut the strip of cloth 49 or sheet of other material merely by the descent and severing action of the blades or knives 46, all as will be readily understood.

The suction conveyer or transporting appliance, including its operating mechanism, for carrying away these cut cloth sections and depositing them in the same relation on a reception table, so that pieces of the same kind and shape will be piled one on top of another in succession, comprises the following specified cooperating instrumentalities.

Two rails or tracks 51 and 52, one at each side of the machine, are employed, each being supported by three, spaced, rock-arms 53, 54 and 55 constituting a parallel motion mounting therefor and pivotally connected at their upper ends to the corresponding rail or track.

Each such rockable, track-supporting arm 53 is hinged or rockingly mounted at its lower end in a bracket 56 on the end of a table extension 57 mounted on or forming part of the main-frame, each intermediate arm 54 is similarly supported directly on the main-frame and each remaining arm 55 is fixedly mounted on a suitably-journalled cross-shaft 58 supplied at one end with another arm 59 (Figures 2, 5 and 10) equipped with an antifriction roller 61 bearing on the edge of a cam 62 interposed between and pinned to the gear 41 and the associated eccentric 43.

It will be clear, therefore, that the regular rotation of gear 41 brings about a like revolution of cam 62 and this in turn rocks the pair of arms 55 causing the raising and lowering of the two, companion, spaced rails or tracks.

The carriage slideable on these tracks or rails comprises a plurality of horizontal, hollow, parallel, sheet-metal members 63 spaced apart slightly and each having a number of staggered holes or apertures 64 through its bottom wall.

The ends of these suction-chamber members toward the cutting appliance are closed by blocks 65 and are also connected to a supporting cross-bar 66 equipped at its opposite ends with grooved wheels or rollers 67 resting on and adapted to roll on the top faces of the two rails.

At their other ends all of these perforated suction-members are connected to and communicate with the interior of a transversely-disposed manifold 68 likewise fitted with grooved rollers 69 at its opposite ends adapted to travel on the rails, such manifold by a plurality of pipes or conduits 71 connecting with any suitable source of suction or sub-atmospheric pressure, such as an ordinary suction or vacuum pump.

To reciprocate this suction conveyer carriage, the following coacting mechanical elements are used.

A slotted, slideable member 72 (Figures 3 and 4) having rack-teeth 70 along the bottom margin of the slot and guided in its horizontal reciprocations by upper and lower blocks 73 and 74 secured to the side of the main-frame accommodates in its aperture or slot the pinion end portion 75 of a cross-shaft 76 revoluble in bearings 77 and 78 of the main-frame, with the pinion teeth in mesh with those of the rack. 75

This rack at its opposite terminal portions has two anti-friction rollers 79 and 81 (Figure 3), the former bearing on the edge of cam 82, heretofore mentioned, and the latter coacting with the edge of another somewhat-differently shaped cam 82 associated and revoluble with gear 29 in the same manner that cam 32 is rotated by its gear 27.

One of these cams pushes the rack in one direction and the other cam forces it in the opposite direction whereby through the small gear or pinion 75 shaft 76 is oscillated.

Two gears 83 and 84 keyed to shaft 76 are in mesh with two inverted racks 85 and 86 slidably mounted by guides 87 on the opposite sides of the main-frame, the extreme untoothed end of each such rack-bar (Figure 6) having secured thereto a vertically slotted bracket 88, the slot 89 of which accommodates a guiding lug 91 on the corresponding end of the manifold member 68, whereby the carriage may be slid on the tracks without interference with its vertical movements heretofore specified. 100

Internally the manifold has an oscillatory valve 92 the shaft 93 of which outside of the manifold is supplied with a collar 94 fitted with an outstanding pin or lug 95, the collar having a rod 96 hinged thereto at 97 and slidably extending through an aperture in a swivelled block 98 with a coil expansion spring encircling the rod bearing at its opposite ends against the block and against a shoulder on the rod, whereby to 110 give the valve a snap spring action, by the spring passing by dead center as is well understood.

To operate the valve, an upstanding bar 101 (Figure 6) is mounted on the part 57 in such position that when the suction conveyer is beneath the raised cutters or blades and is lowered to engage the severed cloth patterns or sections, the pin 95 will engage the upper end of the stationary element 101 and cause the opening of the valve and the application of the suction internally to the plurality of perforated hollow members constituting the suction portion of the conveyor. 120

Similarly, the end of rack-bar 51 is supplied with an upright post 102 (Figure 6) which the same pin or lug 95 engages when the conveyor is lowered over the receiving table, whereby the valve is again closed thus terminating the suction in the conveyor and 125

permitting the transported severed sheets or pieces to drop on the table.

When the suction appliance descends on to the cut sections of the cloth to be picked up, the right hand end portion of such sub-atmospheric device overlaps the advance end of the uncut supply of the cloth which leads from a supply roll, not shown, and as the conveyor travels to the left it pulls along the cloth supply with it beneath the cutting blades which are then elevated in inoperative position.

This cloth feeding action is facilitated or aided by grippers which mechanically grasp the cloth and feed it along, but in the present instance these grippers do not engage the front or advance portion of the supply but coact with the cloth at a point back thereof so that the strain of unrolling the supply from the stock roll will not be imposed on the traveling suction appliance.

As is perhaps more fully shown in Figures 1 and 11, this cloth gripping and feeding device includes a cross-bar 111 located beneath the cloth supply and secured at its opposite ends by brackets 112 to the two rack-bars 85 and 86 so that it participates in their backward and forward movements.

Above such cross-bar and mounted on up-standing brackets 113 at opposite sides of the machine on brackets 112 I employ a vertically movable recessed apertured bar 114 guided in its reciprocations by guide lugs 115 on the inner faces of the brackets.

Both sides of the machine are alike in this respect and consequently a showing and detailed description of one side will suffice for a full understanding of the structure.

Each end of the bar 114 is supported from above on the corresponding bracket 113 by a toggle 116 which when straightened forces the bar 114 down and when collapsed or broken causes the elevation or rise of the bar.

Bar 114 carries any suitable number of clamping-plates 117 each supported beneath the element 114 on one or more stems 118 each extended upwardly through a hole in the part 114 and supplied at its upper end with a nut or collar 119 limiting its descent, a coil spring 121 encircling the stem and pressing the plate down by bearing at its lower end against the top face of the plate and at its upper end engaging the end wall of a recess in bar 114 receiving such spring.

Thus when the toggles are straightened these one or more clamping-plates will grasp the cloth between itself or themselves, as the case may be, and the registering underlying plate 111.

When the toggles are collapsed, the cloth will be free thus permitting this clamping mechanism to move to position for a new hold on the cloth.

The toggle operating mechanism includes a bracket 122 at each side of the machine

supporting a pin or lug 123 in register with the middle of the toggle to collapse the latter at the proper moment as shown in Figure 11.

As is shown in Figure 1, another properly positioned pin or lug 123 is used to straighten each toggle by engagement with its knuckle when this cloth gripping device is in position for grasping the cloth to feed it forwardly.

From the above description and the accompanying illustrations, it will be seen that the cloth is advanced to the cutters, that the latter descend severing the cloth beneath them into sections, that the cutters ascend, that the suction appliance simultaneously conveys away all of the cut portions of the cloth and deposits them in corresponding piles and that the cloth feeding mechanism is operated in proper timed relation for correct coaction with the other parts of the mechanism.

The purpose of spacing apart the apertured or perforated members through which the suction is applied to the cloth is to prevent the sheet of the latter from becoming wrinkled or crumpled by a large body of inflowing air adjacent to the suction elements assuming that they were of large area. By subdividing the air which must necessarily flow, even through the cloth itself, during the application of the suction, such tendency for the cloth to become disturbed and wrinkled or crumpled inwardly away from the edges or margins of the suction members is overcome. If one large apertured suction member only were used, the sheet of cloth would probably not lie flat and smooth against its under surface when the suction was applied, due to the inflowing air currents around the periphery of such member. This subdivision of the air which passes inwardly about the suction conveyor and through the cloth itself is believed to be a new feature in structures of this character.

The invention is not limited and restricted to the precise and exact details of structure but is susceptible of a variety of embodiments and many minor mechanical changes may be made in the structure shown and described without departure from the invention and without the sacrifice of any of its substantial benefits and advantages.

I claim:

1. In an appliance of the character described, the combination of a suction conveyor constructed to transport a sheet in flat condition, means to operate said conveyor, and means to prevent distortion of the sheet to be transported by the conveyor when the suction of the latter is applied to such sheet.

2. In an appliance of the character described, the combination of a suction conveyor constructed to transport a substantially porous flexible sheet in flat condition, means to operate said conveyor, and means

to prevent wrinkling of the sheet to be transported by the conveyor when the suction of the latter is applied to such sheet.

3. In an appliance of the character described, the combination of a suction conveyor comprising a plurality of adjacent apertured spaced hollow bodies with suction applied to their interiors and with air admitted between said bodies, means to move 10 said conveyor, and means to control the suction applied to said bodies.

4. In an appliance of the character described, the combination of a conveyor comprising means to apply suction to the body 15 to be conveyed over a plurality of spaced areas, and means to admit air to said body between said areas to prevent distortion of the body to be transported by the conveyor when the suction is applied, and means to 20 operate said conveyor.

5. In an appliance of the character described, the combination of means to cut a sheet of material into parts, a suction-conveyor to transport a plurality of said cut 25 parts simultaneously and deliver them in their original relation to one another, and means to operate said conveyor.

6. In an appliance of the character described, the combination of means to cut a sheet of material into parts, a suction-conveyor to transport a plurality of said cut parts simultaneously and deliver them simultaneously in their original relations to one another, means to operate said conveyor, and 35 means to advance another sheet section after the removal of the cut parts for subsequent like severance and transportation of its parts.

7. In an application of the character described, the combination of means to cut a 40 sheet of porous material into a plurality of parts, a suction-conveyor to simultaneously

transport said parts and deposit them simultaneously in their original relations to one another, means to operate said conveyor, 45 means to prevent wrinkling of the porous parts of the material to be transported by the conveyor when the suction of the latter is applied thereto, and means to advance another sheet section after the removal of the 50 cut parts for subsequent like severance and transportation of its parts.

8. In an appliance of the character described, the combination of means to cut a sheet of substantially porous material into 55 a plurality of parts, a conveyor comprising means to apply suction to the severed parts of the sheet to be conveyed over a plurality of spaced areas and to admit air to said parts between said areas, means to operate 60 said conveyor to transport the cut sections of the material and deliver them in their original relations to one another, and means to advance another sheet section after the removal of the cut parts for subsequent like 65 severance and transportation.

9. In an appliance of the character described, the combination of means to cut a sheet of substantially porous material into 70 a plurality of mating parts, a suction-conveyor comprising a plurality of spaced apertured hollow bodies with suction applied to their interiors and air admitted between said bodies, means to move said conveyor to transport the plurality of cut parts of the sheet 75 and to deliver them in their original relations to one another, and means to advance another sheet section after the removal of the cut parts for subsequent like severance and transportation. 80

In witness whereof I have hereunto set my hand and seal.

ARTHUR J. EVERSON. [L.S.]
